Claims priority, application France March 21, 1957

5 Claims. (Cl. 57—58.83)

When a double-twist hollow spindle is used for throwing or twisting threads, fibres or like flexible elongated members (hereinafter designated "thread"), it is necessary to impart a certain degree of tension to the thread between the point at which it leaves a supply bobbin placed on the hollow spindle and the point at which, on leaving the hollow spindle, it forms a "balloon" on its upward journey as far as a thread guide placed above the supply bobbin. This tension should have a predetermined value which depends, *inter alia*, on the nature and on the count or number of the thread, and also on the speed of rotation of the hollow spindle. It should be sufficiently low to prevent damage to the thread but sufficiently high to stabilize the balloon, *i.e.* to prevent the diameter thereof from increasing beyond a certain limit, due to the action of centrifugal force.

Many devices have already been proposed with a view to solving this problem, some of said devices acting by friction on the thread, for example by nipping the thread between a movable ball and the internal wall of the hollow spindle, while others consist of a braked element to which there is imparted a rotatory movement by the thread unwinding from the supply bobbin.

It is an object of the present invention to provide a device for use in twisting or throwing machines using a hollow spindle through which the thread is removed from a supply bobbin.

It is a further object of the present invention to provide such a device which will make it possible to regulate the tension applied to the thread in twisting machines using a hollow spindle.

It is a further object of the present invention to provide such a device which may be used in conjunction with an inlet section detachable from the hollow spindle.

Further objects of the present invention will become apparent hereinafter.

The present invention provides a device comprising a thread guide in combination with a double-twist machine of known type, the vertical hollow spindle of which is surmounted by a coaxial inlet element, said thread guide bearing on a surface of the inlet element, which surface is positioned in the path followed by the thread between the supply bobbin and the hollow spindle; it should be noted that the coaxial inlet element may be formed by the support for the bobbin supplying thread to the double-twist machine or the inlet element may be a piece separate from the bobbin support, said separate piece being removable or non-removable from the double-twist machine. As a result of the manner in which the thread guide is arranged, the thread unwound from the supply bobbin has to sweep constantly over said bearing surface before entering the hollow spindle.

The present invention also provides a thread guide for use in twisting machines provided with a hollow spindle through which threads, fibres and like flexible elongated members from a supply bobbin may be drawn, and an inlet element for said spindle, characterized in that the guide is adapted to bear on a surface of the in-

2

let element which surface is also part of the path followed by thread on its way to the interior of the hollow spindle.

One particularly simple embodiment of the invention consists in giving the thread guide the shape of a letter T having asymmetrical arms. The stem of the T engages inside the inlet element and one of the arms of the thread guide bears on a surface of the said inlet element. This arm may be loaded to a greater or lesser degree by means of weights, so as to regulate the pressure which it exerts on the bearing surface and consequently also the tension exerted on the thread during the twisting operation. The other arm carries near its end one or more eyelets or other openings, the position of which is such that the thread passing through them is compelled to constantly sweep over the bearing surface.

If the inlet element surmounting the hollow spindle is removable from the twisting machine with which it is associated, it will be possible to manipulate it more easily if the thread guide is fast with the said element. This may be very easily provided, in accordance with a special embodiment of the invention, by the portion of the thread guide which has passed through the said element being cranked substantially in the plane determined by the arms of the T and the vertical stem thereof and opposite the arm thereof which carries the eyelet or eyelets or other openings. It is extremely surprising to find that the thread does not wind round the said stem when it is cranked as indicated hereinabove, whereas this inconvenience does result and causes breakage when the stem is cranked in a different manner. In order that the thread guide may be separated from the inlet element when desired, the cranked stem and/or the inlet element may consist of a plurality of elements which have been assembled by any known means, for example by screwing.

The device according to the invention is particularly simple and enables the tension exactly required to be exerted on the thread, whilst giving the necessary value to the weight regulating the pressure of the thread guide on the bearing surface; furthermore, the said tension remains remarkably constant during the throwing or twisting operation.

Two embodiments of the device in accordance with the present invention are illustrated in the accompanying diagrammatic drawings, in which:

45 Figure 1 is a cross section through a front elevation of a twisting machine in which the support carrying the supply bobbin also forms an irremovable inlet element, and

50 Figure 2 is a cross section through a front elevation of a twisting machine having a removable inlet element.

In the embodiment illustrated in Figure 1 a double-twist machine of known type is shown comprising a rotatable hollow spindle 1 (adapted to be driven by means which are not shown) and a fixed coaxial support 2 carrying a thread supply bobbin 3 and provided with a channel 4 through which the thread enters the hollow spindle.

A T-shaped thread guide is provided having a stem 5 which penetrates into the channel 4, an arm 6 provided near its end with eyelets 7, and an arm 8 carrying a weight 9. The arm 8 of the said thread guide bears on a ring-shaped surface 10 of the support 2.

In operation, thread 11 is unwound from the bobbin 3 and passes through the eyelets 7 before entering the channel 4 and then the hollow spindle 1, thus imparting a rotatory movement to the thread guide.

The respective positions of the eyelets 7 and of the bearing surface 10 are such that the thread constantly sweeps over the said surface during the use of the device for effecting a twisting operation.

In the embodiment illustrated in Figure 2 a double-twist machine of known type is shown comprising a rotatable hollow spindle 20 (adapted to be driven by means which are not shown), a fixed support 21 carrying a thread supply bobbin 22 and a removable inlet element 23 provided with a passage 24, the axis of which coincides with that of the hollow spindle 20.

A T-shaped thread guide is provided having a stem 25 penetrating into the passage 24, and arm 26 provided with eyelets 27 near its end, and an arm 28 carrying a weight 29. The stem 25 is cranked at 30 in the plane determined by the arms 26 and 28 and the stem 25, but in the direction opposite to the arm 26. The thread guide and the inlet element are thus locked into one another; their manipulation, for example for the purpose of placing the bobbin in position, is facilitated, since there is no longer any risk that the thread guide may slide out of the inlet element.

The arm 28 of the thread guide bears on an annular bearing surface 31 on the inlet element 23.

As in the first embodiment the thread 32 constantly sweeps over the surface 31 during the throwing or twisting operation.

The invention has been described with reference to double-twisting or throwing, i.e. with regard to the case wherein two turns of twist are imparted to a thread, for one revolution of the hollow spindle. This application is of some considerable commercial importance, but the invention is not limited thereto and may be used in every case wherein use is made of a vertical hollow spindle, whether a single turn of twist is imparted to the thread for one revolution of the hollow spindle, or, on the other hand, more than two turns of twist are imparted for each revolution of the hollow spindle.

Although the present invention has been described with particular reference to specific details, it is not intended that such details shall be regarded as limitations upon the scope of the invention except insofar as included in the accompanying claims.

What I claim and desire to secure by Letters Patent is:

1. A device for throwing and twisting threads, fibres and like flexible elongated members comprising, in combination with a twisting machine having a rotatable hollow spindle, a channeled coaxial inlet element disposed thereon and provided at its upper end with a ring-shaped surface, and a thread supply bobbin disposed around said inlet element, a thread guide having a portion thereof bearing on the ring-shaped surface of the inlet element

and a portion provided with at least one eyelet situated below the level of the upper end of the inlet element, so that thread passing from the supply bobbin into the hollow spindle travels over the ring-shaped surface in contact therewith.

2. A device according to claim 1, in which the thread guide approximates the shape of a letter T having a stem and asymmetrical arms, the stem extending downwardly inside the inlet element, one of the arms of the T bearing on the said surface of the inlet element, a weight loading said arm to regulate pressure exerted by the arm on the said surface, and the other arm of the T being provided with at least one opening for the passage therethrough of the said thread.

3. A device according to claim 2, in which the said stem of the T is cranked substantially in the plane determined by the said arms of the T and the said stem thereof in a direction opposite to the arm provided with the opening.

4. A thread guide for a twisting machine having a hollow spindle through which thread may be drawn, a thread supply bobbin for said spindle and an inlet element extending through said bobbin and provided at its upper end with a bearing surface, said thread guide being in the shape of a letter T having a stem and asymmetrical arms, the stem of the T engaging inside the inlet element, one of the arms bearing on the said surface of the inlet element, a weight loading said arm to regulate the pressure exerted thereby on the bearing surface and the other arm of the T being provided with at least one opening for the passage therethrough of the said thread, said opening being situated below the level of the upper end of the inlet element.

5. A thread guide according to claim 4, in which the said stem of the T is cranked substantially in the plane determined by the said arms of the T and the said stem thereof in a direction opposite to the arm provided with the opening.
